Primary Examiner — Phillip S Hyder*Assistant Examiner* — Roselynne Cody(74) *Attorney, Agent, or Firm* — Haverstock & Owens LLP(57) **CLAIM**

We claim the ornamental design for a ratcheting tool with a flip out handle, as shown and described.

DESCRIPTION

FIG. 1 is a front view of the ratcheting tool with a flip out handle;

FIG. 2 is a back view of the tool;

FIG. 3 is a left side view of the tool;

FIG. 4 is a right side view of the tool;

FIG. 5 is a top view of the tool;

FIG. 6 is a bottom view of the tool; and,

FIG. 7 is a front view of the tool in an L-handle configuration.
